ATTACHMENT FOR HOLDING BAGS AND
OTHER ARTICLESJames Papalexis, Ashtabula, and Oliver Warren
Johnson, Geneva, Ohio

Application December 15, 1944, Serial No. 568,760

1 Claim. (Cl. 211—31)

1

This application applies to valuable improvements in certain elements composing the attachment to dining room tables and bars for receiving and holding lady customers' pocketbooks, valuable pieces of neckwear that is subject matter of our original application now pending in the United States Patent Office under Serial No. 500,639½, filed August 31, 1943, which became United States Patent 2,369,978 on Feb. 20, 1945.

One of the objects of this invention is to provide a garment holder of the type described that is adapted to be horizontally attached, near the edge, on the underside of the top part of said dining table, in such manner that the D-clamp 1 will be held horizontally flat against the underside of said table, while in the unused or dormant position for the purpose of not interfering with the legs or clothing of patrons, and yet, instantly ready to be pulled down into its operating position by patrons when they are seated and want to use it.

Another object of this invention is to provide adhesive pads 4 and 7 on the lower ends of D-clamp 1 and gooseneck 8 in order to prevent injury to the finest fabrics and to give a firmer and additional grip as well as a greater adhesive hold against slippage of such articles as books, patent leather pocketbooks and bags, heavy silken articles and similar things than would ordinarily not be possible with the same degree of pressure by said spring without said adhesive pads.

The following is the specification of the "Midget," the smallest of the garment holder line covered by our patent application Serial No. 500,639½, filed August 31, 1943.

The following numerals each designate a single member or part thereof at all times and in all places including the descriptive matter attached thereto.

Fig. 1 shows side elevation of the entire assembly including D-clamp 1 in operative position, and main frame or base plate 18 in position to be rigidly attached to a horizontal supporting surface.

Fig. 2 shows front view of Fig. 1 in operative position, the dotted lines extending out from one side of said view, shows D-clamp 1 in its left dormant, or unused position.

Fig. 3 shows plan view of Fig. 1 with central portion of main frame 18 cut away showing spring 15, jaws 2, lugs 19 and pin 13 all in operative position.

Fig. 4 is a perspective view of hinge lug 9, hole 55 of its dormant or operational positions. When

2

10, head 11, lip 11—a, frame 6, spring 15 and anchorage means 14.

No. 1, D-clamp, the belly of which forms the larger part of the parking space of the holder, this parking space being the main object of the invention.

No. 2, jaws on the upper end of D-clamp 1 designed to pivotally connect with hinge lug 9 on C-frame 6.

No. 3, recess in jaws 2 designed to clear hinge lug 9 while the former is being operated.

No. 4, rubber pad, on the lower end of D-clamp 1, designed to engage rubber pad 7 on gooseneck 8, thereby preventing damage to articles held between pads 4 and 7, as well as furnishing an adhesive surface to better grip and hold books, silken articles and patent leather articles between them, and also to prevent a loud clicking sound, if there were no such pads, when the D-clamp 1 was released and let fly against the bare end of gooseneck 8, as would be the case where mischievous children are.

No. 5, pin in jaws 2.

No. 6, C-frame acting as the backbone of the holder and adapted to cooperate with clamp 1 by providing the hinge lug 9 for said D-clamp 1 to swing on; spring 15 to anchor to; pivot head 12 to swing on pin 13; friction head 11 at said C-frame's upper end and its (frame 6) middle section formed into a concaved body thereby helping to form the parking space so valuable to this invention; the gooseneck on the lower end of said C-frame 6's extreme lower end 8 and cushion rubber pad 7 on said extreme end 8, the latter also adding its quota to enlargement of said parking space.

No. 7, rubber cushioning pad on end of gooseneck 8 whose function has been described.

No. 8, gooseneck forming the lower section of C-frame 6 whose function has been described.

No. 9, hinge lug on C-frame whose function has been described.

No. 10, hinge hole in head 12 for pin 13, this hole being the pivotal point of movement of C-frame 6 in said frame's sidewise swing from right to left as it assumes its dormant position on the one hand, or its vertical operating position on the other hand, the dormant position always being parallel to the base plate 18 when the latter is attached to a horizontal support.

No. 11, friction surfaced top on head 12 designed to frictionally engage flat spring 17 and thus hold said head 12, and consequently the body of C-frame 6 and its attachments in either one

not in use, said holder is supposed to be always in its dormant position, and when wanted for use, the patron simply grasps the lower part of D-clamp 1, pulls it down to its operating (vertical) position, pulls up D clamp 1, inserts article desired and lets go, whereupon said D-clamp 1 grips and securely holds said inserted article until same is removed by the patron. The top edge of surface 11, it will be noticed on the drawing, is flattened for the purpose of forming a surface whereby spring 17 may exert a better restraining influence on the head 12 while same is in the vertical or operating position. Likewise, said flat surface on head 12 is wide enough to insure that its engagement with spring 17, when 12 is in its dormant position, will hold C-frame 6 and all of its attachments in a parallel position to said horizontal main frame 18.

No. 11-a, an extension, or lip, provided on each side of the friction head 11 designed to extend out and away from the center of surface 11 far enough to so engage spring 17 that the paralleling of C-frame 6 will be accomplished as previously described.

No. 12, head of C-frame 6 pivotally operating on pin 13 in lugs 19 for purpose of carrying friction surface 11 so said 11 can perform the service designed for it as elsewhere explained.

No. 13, pin operating in pin holes of lugs 19 as described.

No. 14, spot welded anchorage part of C-frame 6 rigidly holding the anchor ends 16 of spring 15. These ends may be anchored to C-frame 6 by any other suitable means.

No. 15, helical spring, made of satisfactory spring wire, or other suitable material may be used if more satisfactory service can be had.

No. 15-a, compression arms of spring 15. Said arms designed to exert sufficient pressure on D-clamp 1 to cause the latter to grip and hold the articles placed within its grip.

No. 15-b, cross-bar integral with arms 15-a of spring 15 designed to engage the top surface of D-clamp 1 and compress same against pads 4 and 7 by means of pressure transmitted to it through arms 15-a.

No. 16, anchor ends of spring 15 for purpose previously described.

No. 17, a flat crescent shaped compression spring, one end of which is rigidly attached to the under surface of base plate 18, at one end thereof, while the other end of said spring slidably engages the same under surface of said base plate 18 at the latter's other end, while the bowed center of said spring 17 frictionally engages the friction surface 11 in maintaining the said dormant and operational positions of said C-frame 6 and D-clamp 1.

No. 17-a, bent, or sled runner end of spring

17 designed to permit same to slidably engage the under surface of said base plate 18.

No. 17-b, rigid attachment of one end of spring 17, as described, by means of screws, bolts or otherwise.

No. 18, flat, oblong base plate (sometimes called main frame 18) adapted to be horizontally attached to a horizontal support, and from the underside of said base plate two lugs 19 depend in parallel spaced relation to each other and to the longitudinal central line of said base plate 18.

No. 19, lugs rigidly attached to and depending from the underside of said base plate 18, whose position and functions have already been described.

No. 20, large parking space created by the extensively curved belly of D-clamp 1; crescent shaped C-frame 6 and the gooseneck 8, the major element of service and importance in the holder.

We claim:

A garment holder comprising a flat base plate adapted for attachment to the lower side of a horizontal support, spaced parallel lugs dependent from said base plate, the head of a C-shaped frame horizontally pivoted to said lugs, a flat spring attached to the underside of said base plate, said spring operatively engaging said head, said C-frame adapted for angular movement, a gooseneck formation of the lower section of said C-frame, a cushion pad on the end of said gooseneck, an outward extension on and adjacent to the head of said C-frame, the top end of a D-clamp pivotally attached to said extension, the lower end of said D-clamp enclosed by a cushion pad, said pad adapted to operatively engage the pad on said gooseneck, one portion of a helical spring rigidly attached to said head, the other portion of said spring adapted to engage in compressed relation the upper top surface of said D-clamp adjacent said D-clamp's pivotal connection to said head.

JAMES PAPALEXIS.
